PAPER TOWELING

Donald T. Appleman, Cincinnati, Ohio, assignor to
The Procter & Gamble Company

Filed June 19, 1974, Ser. No. 480,642

Term of patent 14 years

Int. Cl. D5—06

U.S. Cl. D59—2 A

The single figure is a plan view of my new design for a paper toweling. The design units are representative in the longitudinal direction, with a typical repeat being indicated by the repeat lines shown.

I claim:

The ornamental design for a paper toweling, as shown and described.
